G. Kennedy,
ATTORNEY

UNITED STATES PATENT OFFICE

SAMUEL SILVERS, OF WATERLOO, IOWA

HUMIDIFIER

Application filed November 19, 1930. Serial No. 496,587.

My invention relates to improvements in humidifiers, and the object of my improvements is to supply a device of this class adapted for humidifying the air in an inclosure 5 quickly and effectively, and to maintain a suitable degree of humidity therein according to hygienic necessities.

A particular improvement is the construction of absorbent devices for liquid in the 10 apparatus, such devices being assembled and unitarily supported in a manner rendering them easily removable together for renewals or for cleaning.

Other improvements will be hereinafter 15 specifically alluded to herein, and it is to be understood that modifications may be effected in the apparatus variously without thereby departing from the protection of the claims or from the scope of this invention.

20 In my apparatus, I have successfully reduced to practise the means which are hereinafter described and claimed, and which are illustrated in the accompanying drawings, in which Fig. 1 is a medial longitudinal 25 vertical section of my humidifying apparatus, with certain elements shown in side elevation. Fig. 2 is a rear elevation, and Fig. 3 a front elevation of the device. Fig. 4 is an end elevation of the absorbent liners as 30 unitarily assembled together in a single humidifying unit, with parts broken away in a vertical transverse section thereof. Fig. 35 5 is a top plan of the complete apparatus, with parts broken away, and showing the hinged top closure in an open position. Fig. 6 is a fragmentary horizontal section and with parts in top plan of portions of the 40 humidifying sheets and their supports with end connections, and on an enlarged scale.

45 The numeral 1 denotes a housing, with closed bottom and sides, imperforate, but whose front and rear walls 3 and 5 respectively have in their upper portions relatively large like circular apertures 2, the front opening 2 being preferably but not necessarily covered by a foraminous grating 4. The top of the housing has a large rectangular opening 9, closed by an arched cover 6 on 50 hinges 7 and having near its free longitudinal edge a medial finger knob 8.

Referring to said Figs. 1 and 2, the numeral 10 denotes an electric motor at the rear of the housing 1 with its armature shaft 11 extending centrally through the rear wall aperture 2, and supported on arms 14 secured to the inner wall of the rear part 5 of the housing. On said shaft within the housing is a radially vaned fan 12 surrounded by a wire and open guard frame 13.

55 Removably mounted within the housing 1 is a multifold lining device, which may be inserted through or removed from the top opening 9 quickly and easily, the fingers of the operator being protected by said grating 13 around the fan wheel 12, whether the latter is or is not in rotation.

60 The constituents of this lining device are similar but vary only in relative positions and sizes being nested concentrically in spaced relation, and composed each of one or more contacting layers or sheets 16 of absorbent material, such as blotting paper or the like, supported upon both outer faces by reticulated wire nettings 15 which prevent them from collapsing when wet and softened. As shown in Fig. 4, these liners 15 and 16 65 are arranged regularly as upright from their bottom edges and connected medially by arched parts which are concentric, air passages thus being left throughout between the liners from front to rear thereof, and with the arched parts preferably concentric also with the centrally alined motor shaft 11. To rigidly connect and support the lower parts of these liners as an unitary structure, 70 I have employed the following means.

75 Referring now to said Figs. 4, 5 and 6, and particularly to the enlarged detail shown in Fig. 6, the straight upright end parts at front and rear of each liner combination 16 and 15 is inclosed and clasped fixedly by a channeled bar 19 soldered or otherwise affixed thereto. Secondly, the lower parts of the channel bars 19 are inclosed and the liners 16 and 15 held in fixed and spaced relation by horizontal and rectangularly convoluted foot-bars 17 likewise soldered upon the channel bars 19. Finally, at each end of the unitized liners, a bottom transverse flat bar 18 is 80 soldered upon and across the outer portions 85 of the liner combination.

of the convoluted bars 17. Thus the whole structure is stiffened and reinforced, and can be handled as an unitary construction.

As shown in said Fig. 5, each liner 15 and 5 16 has a top medially longitudinally positioned aperture 20 through which water or other suitable liquid may be poured through the liners without removing their aggregation from the housing 1, and preferably the 10 apertures 20 are offset from each other in the alternated liners, so that when the liquid is poured therethrough, it is diverted lengthwise along the arched tops of the liners in a way which wets the tops of the liners initially, the liquid thence moving down the 15 absorbing sheets 16 into the bottom of the housing which provides a tank in which the lower parts of the liners are immersed. Capillary attraction of the sheets 16 then keeps them 20 wet until the liquid supply exhausts or is renewed as before.

The motor in action causes its rapidly rotating fan wheel 12 to drive a strong draft or air from the rear wall opening to the front 25 wall opening 2 and out into the room or other inclosure. The apparatus may be removably supported upon the top of a stand or other elevated construction in order to thereby set up air currents for equable air distribution.

When the liner assembly after a time has 30 its absorbent sheets coated more or less with adherent impurities from the passing air drafts, the unitary assemblage may be removed as one body for cleansing, and then returned to the device.

Having described my invention, what I claim as new, and desire to secure by Letters Patent, is:

40 1. A humidifier, comprising a housing with apertured end walls above a bottom tank part, means for driving an air current through it and out through its front wall aperture, and an assemblage of spaced rigidly connected liner plates in the housing adapted to have their lower portions immersed in liquid in said tank part, and composed of absorbent material adapted to conduct the liquid upwardly by capillary attraction, said 45 liners being shaped and arranged as concentric arches with depending vertical parts.

2. A humidifier, comprising a housing with opposite wall apertures above a tank part, a unitary liner device seated removably in said housing to be submerged in its 55 lower part only by a liquid deposited in said tank part, said liner device consisting of an assemblage of spaced absorbent sheets shaped and arranged respectively as concentric 60 arches intermediate said opposite wall apertures and capable of conducting liquid from the tank part upwardly by capillary attraction, foraminous rigid sheathing for said sheets, and stepped rigid devices mounted across the lower end parts of the sheets and

sheathing and secured to the latter to render the liner device a unitary structure.

3. A humidifier, comprising a housing with opposite wall apertures above a tank part, a liner device positioned within said housing 70 removably and consisting of spaced upright absorbent materials, sheathing of reticulated material positioned upon opposite faces of each said materials to rigidly maintain its relative position, means for propelling air 75 through the housing, and convoluted rigid end connections between the lower end parts of said sheathing and secured thereto to maintain the liner device as an unitary structure for traversing said top opening of the 80 housing in entry or removal.

In testimony whereof I affix my signature.
SAMUEL SILVERS.
